BY C. P. Goepel

his ATTORNEY

UNITED STATES PATENT OFFICE

ALBERT ENTENMAN, OF BROOKLYN, NEW YORK

FRAME

Application filed June 3, 1927. Serial No. 196,172.

This invention relates to improvements in frames and more particularly to glass supporting frames such as door and window sashes and the like.

5 It is a matter of common knowledge that as the wood of the frame becomes seasoned and as the putty used to retain the glass in place dries, the adhesive qualities of the putty degenerate and disintegration takes place 10 with the result that the putty falls out and leaves the edge of the glass exposed for the entrance of water, dirt, dust and the like, besides presenting an unsightly appearance.

The primary object of the present invention is to prevent the putty which holds the glass in the frame from falling out, should the same lose its adhesive characteristics and become loosened.

Another object of the invention is to reduce 20 the area of the putty exposed to the action of the elements without reducing its area of contact with the frame, thus preserving the adhesive action between the putty and the frame.

25 A further object of the invention is to guide a putty knife during the application of the putty to the frame and insure a smooth uniform finish to the exposed outer surface thereof.

30 Still another object of the invention is to support the glass in the center of the opening in the frame and insure its proper location with relation thereto during the application of the putty.

35 A feature of the invention is the longitudinally disposed groove which receives and entraps the putty to effectively prevent its falling away from the frame and glass and presenting an unsightly appearance.

40 Another feature of the invention is the inclined exposed edge of the bead forming the outer wall of the groove which serves as a guide for a putty knife during the application of the putty to the frame to insure a smooth uniform finish to the completed operation and reduce the area of the putty exposed to the action of the elements, thereby retarding its disintegration.

45 A further feature of the invention is the shoulder in the glass receiving rabbet which

serves to support and center the glass with relation to the opening in the frame.

The above and other objects may be attained by the use of this invention, one embodiment of which consists in the novel construction, combination and arrangement of parts, which will be fully set forth in the following specification, and illustrated in the accompanying drawing in which:

55 Figure 1, is a side view of a window, the frame of which is constructed in accordance with this invention,

60 Figure 2 is an enlarged fragmentary sectional view taken on line 2—2 of Figure 1,

65 Figure 3 is an enlarged sectional view similar to Figure 2 showing the same prior to the application of the putty, and

70 Figure 4 is a fragmentary perspective view illustrating the manner in which the guide surface is utilized.

75 Referring to the drawings in detail, the frame designated generically 10 comprises bars 11 which are attached together at their ends to form a complete structure.

Each frame member 11 is rabbeted to form a stop shoulder 12 against which the inner face of the edge of the transparent panel 13 rests.

80 A groove 14 is formed in each member 11 between the shoulder 12 and the outer side thereof and the innermost end of this groove terminates a short distance from the shoulder 12 to form a seat 15 for the marginal edge of the panel 13.

85 The groove 14 together with the outer side of the member 11 forms a longitudinally extending bead 16, the edge face of which is inclined as at 17 to form a guide against which a putty knife or similar tool is pressed during the application of putty.

90 As shown in the drawings, the outer edge of the bead 16, that is the edge farthest from the groove 14, lies in a plane with the seat 15 so as to partially overlie the glass 13. Introduction of the glass 13 into the frame is 95 affected by inserting one edge into the groove and then seating the opposite edge against the shoulder 12, whereupon the glass may be fitted into proper positon. The degree of inclination of the face 17 is such that when the

blade of a putty knife or similar instrument is placed thereagainst, its innermost edge, that is, that next to the glass 13, will lie in a plane with the inner exposed face 18 of the frame member 11. It will thus be seen that the putty when properly applied will in no way overlie and restrict the vision through the glass.

By pressing the putty or other plastic retaining substance into the groove 14 as shown in Figures 2 and 4, it will be apparent that it will tightly adhere to the wall thereof and effectively seal the glass in place to exclude water, dust and dirt. At the same time the disintegrating effect of the elements on the putty is reduced to a minimum by the reduction of the exposed surface of the putty and even though the putty may lose its adhesive qualities, accidental dislodgment of the putty from the frame is precluded.

As will be seen, particularly in Figures 2 and 3, the pane or panel 13 projects beyond the seat 15 into one side of the groove 14. The periphery of the panel thus forms a shoulder inside the groove 14 and the putty, or the like, when it is pressed into the groove 14 is forced behind this shoulder and is retained by the shoulder in the groove, and cannot come out.

While in the foregoing, there has been shown and described one embodiment of this invention, it is to be understood that minor changes in the details and construction, combination and arrangement of parts, may be resorted to without departing from the spirit and scope of the invention as claimed.

What is claimed is:—

A frame to receive and mount therein a transparent panel, the frame having an inside peripheral shoulder against which the panel rests and being provided with an inside peripheral groove adjoining the shoulder and situated between the shoulder and one face of the frame, the panel when in engagement with the shoulder projecting into one side of the groove with its edges spaced from the inner end of the groove, the frame also having an inwardly-extending bead between the groove and said face and forming the side of the groove adjacent the shoulder, the inner edge of said bead being bevelled all around the frame at such an angle that when a tool is laid against said edge it will make contact with the surface of the panel at a point which is flush with the inside of the frame so that the groove may be filled with a plastic retaining substance which can be worked into place by the tool so that said substance does not extend beyond the inside of the frame.

In testimony that I claim the foregoing as my invention, I have signed my name hereto.

ALBERT ENTENMAN.
